SIZE TESTING DEVICE FOR GLOVES

Elmer J. Bliss, Boston, Mass., assignor to Regal Shoe Company, Whitman, Mass., a corporation of Massachusetts

Application June 10, 1932, Serial No. 616,461

6 Claims. (Cl. 33—2)

This invention relates to the size testing of gloves in order to determine the size measurement of any particular gloves whose size it is desired to ascertain. While gloves are supposed to be made in accordance with a certain standard practice of known measurements corresponding to the customary size designations expressed by numerals, nevertheless in commercial practice it is found that there is a good deal of variation 5 from the standard practice by different manufacturers and consequently it is desirable for any dealer using a glove fitting device for measuring the hand to ascertain whether the gloves to be obtained from the manufacturer correspond 10 with such standard scale of measurements.

To this end the present invention comprises, generally speaking, a size testing device for measuring gloves embracing in its construction a form simulating the shape of a human hand and comprising plural, separable, longitudinal sections combined with expanding means interposed between the sections and movable longitudinally thereof to expand the form transversely to any desired degree to properly fit a glove into 15 which the form is inserted and having a glove size indicating scale correlated with the longitudinal adjustment of the expanding means to indicate the size measurement of the glove being tested. This and other features of the invention will be particularly described in the following specification and will be defined in the claims 20 hereto annexed.

In the accompanying drawing I have illustrated one simple and practical form embodying 25 the principles of this invention, in which

Fig. 1 is a plan view of the testing device corresponding to the left hand with the palm uppermost portions being sectioned to more clearly show a part of the interior construction.

Fig. 2 is a side elevation of the form shown in Fig. 1.

Fig. 3 is a transverse section on the plane 3—3 of Fig. 1 with the palm in down-turned position.

Fig. 4 is a transverse section on plane 4—4 of Fig. 1 with the palm downwardly turned.

Fig. 5 is a perspective view showing the outside longitudinal section on the little finger side of the hand.

Fig. 6 is a perspective view showing an element 50 of the expanding means by which the width of the form is varied to fit the form to the interior of a glove being tested.

According to the embodiment of the invention herein illustrated, the manual form which simulates the human hand in shape comprises four 55

separate longitudinal sections 1, 2, 3 and 4, which are transversely bored on a common axis for the reception of a transverse guide pin which, in this form of the device, is preferably made in two axially aligned sections 9, 9^a, each of which is pinned to one member and has telescopic sliding engagement with the adjacent members so as to preserve the sections of the form in uniform transverse alignment, while allowing a greater or less degree of separation to permit them to be 10 spread apart the necessary distance to fit into the interior of the glove being measured in which the form is inserted.

The individual members are provided on their lateral opposed faces with recesses or chambers 5 having inclined lateral faces 6 bearing against similarly inclined faces of wedge-shaped expanding members 10, so that as the wedges are moved forward longitudinally of the sections an increasing spreading action is secured to expand 20 the whole width or girth measurement of the hand. The sections are normally drawn or contracted together by means of a contractile helical spring 12, whose opposite ends are anchored by means of anchoring pins 12^a secured in the two 25 outside members 1 and 4. This contractile spring serves to draw the individual sections together against the interposed wedges which comprise part of the expanding means. A second transverse guide pin 20 is inserted in the expanding 30 members 10 to prevent their longitudinal displacement in relation to one another, while allowing the lateral separation or contraction of the wedges in the process of adjusting the form to any desired size measurement. This guide pin 20 35 is preferably pinned to the middle section 10 and has free telescopic sliding engagement with the registering bores in the adjacent wedge members.

For effecting longitudinal adjustment of the expanding means, I secure in the rear end of one 40 of the form sections a threaded rod or screw 15 which passes freely through a lug 14 attached to the rear end of one of the expanding elements 10 and projects a substantial distance beyond said thrust lug 14. On the projecting end of this fixed 45 screw is placed a threaded nut 16, whose forward end abuts against the thrust lug 14 so that when the nut is screwed inward on the screw shank 15, the expanding means is moved forwardly to expand the form sections to the desired degree. 50 The individual expanding wedges, which form part of the expanding means in this construction, are provided with two wedge portions 10^a and 10^b, one at the forward end and one toward the rear as shown in Fig. 6, thereby providing in- 55

clined expanding surfaces 11 and 11^a for engaging similarly inclined surfaces 6 and 7 of the form sections so as to maintain substantial parallelism between the sections as they are moved 5 toward or away from each other. On the rear end of one of the longitudinally movable expanding members is placed a glove size scale, whose intervals are laid out on the basis of quarter sizes in correspondence with the amount of expansion 10 of the form effected by each unit of adjustment on the scale. The adjacent end of one of the form sections serves as an indicating pointer as it travels over the intervals of the size scale to give the correct size reading on the scale in correspondence with the actual girth measurement 15 around the measuring form. A helical compression spring 18 interposed between the lug 14 and the rear end of the aligned form section serves to yieldingly thrust the lug 14 against the gauging 20 and adjusting nut 16. The laying out of the size scale will depend upon the amount of total expansion imparted to the hand form by any given adjustment of the expanding means.

What I claim is:

- 25 1. A size testing device for measuring gloves embracing in its construction a hand simulating form comprising separable longitudinal sections separated on divisional planes transverse to the breadth of the form and expanding means interposed between the sections and movable longitudinally thereof to separate the sections laterally to any desired degree to properly fit a glove into which the form is inserted, and means associated with the expanding means to indicate the size measurement of the glove being tested.
- 30 2. A size testing device for measuring gloves embracing a hand simulating form comprising longitudinal sections movable widthwise of the form toward and away from each other, and guiding 40 means preventing relative longitudinal displacement of the sections, expanding means interposed between the sections, and longitudinally movable means for adjusting the expanding means to separate the sections to a greater or less degree to 45 fit the form to a glove in which it is inserted, the device being provided with a size indicating scale arranged to show girth measurements in correspondence with variations in longitudinal adjustment of the expansible form.
- 50 3. A size testing device for measuring gloves embracing a hand simulating form, comprising separate longitudinal sections separated from each other on divisional planes in continuation of the spaces between the finger members of the form 55 and longitudinally movable interposed wedge members having lateral inclined plane engagement with adjacent sections of the form to expand the form to fit the interior of a glove, ad-

justing means for adjusting the wedging means longitudinally in relation to the form sections, the wedging means being provided with a size indicating scale associated with one of the longitudinal sections to indicate the size measurement of a glove in which the form is inserted and adjusted to fitting relation.

4. A size testing device for measuring gloves embracing in its construction separate longitudinal sections held against relative longitudinal displacement, interposed expanding wedges also held against mutual longitudinal displacement with relation to one another, means for adjusting said wedges longitudinally of the form to expand the sections laterally and thereby vary the girth measurement around the form, an adjusting thrust nut and screw for effecting longitudinal movement of the wedges, one of the wedge members being provided with a longitudinally disposed glove size scale registering with a fixed point on one of the longitudinal sections of the form.

5. A size testing device for measuring gloves embracing a plurality of separate longitudinal sections comprising a hand simulating form, the sections being provided in their adjacent lateral faces with recesses, wedge members interposed between said sections and projecting into said recesses, transverse guiding means carried by said sections to prevent longitudinal displacement of one section with relation to another, a contractile spring for normally but yieldingly drawing the sections together, and means for adjusting the wedges longitudinally to vary the girth around the sectional form, the wedging means being provided with a size scale arranged to indicate variations in girth measurement in accordance with the longitudinal adjustment of the wedging members.

6. A size testing device for measuring gloves embracing a hand simulating form comprising separable longitudinal sections, a transverse guide pin permitting the sections to move toward or away from each other without relative longitudinal displacement, tensioning means normally tending to draw the sections together, expanding means embracing members having forward and rearward inclined faces forming expansion wedges for forcing the sections apart, adjusting means interconnecting the sectional form with the expanding means comprising a threaded rod and a thrust nut for adjusting the expanding means forwardly, and a yielding spring exerting a counter thrust tending to retract the wedging means, the latter being provided with a glove size scale corresponding to the variations in girth of the form effected by such longitudinal adjustment.
